UNITED STATES PATENT OFFICE.

JAMES LESLIE YOUNGHUSBAND, OF CHICAGO, ILLINOIS.

COSMETIC CASE.

Application filed March 9, 1927. Serial No. 173,800.

This invention relates to a cosmetic case or compact and more particularly to one of improved construction wherein the casing sections are constructed of a non-metallic product such as celluloid, bakelite, casein composition, or similar material, said sections being held in associated relation by means of diametric metal straps hinged to one another and held in place on the respective casing sections by means of wire retaining rings or hoops, thereby providing a cosmetic container of simplified and inexpensive construction without resorting to the use of rivets, screws, or other similar retaining means.

It is an object of this invention to provide a simplified and inexpensive cosmetic container or compact wherein the casing sections are preferably constructed of a non-metallic product such as celluloid and held in associated relation by means of hingedly connected metal straps held in place by wire rings with one of said straps provided with an integral latching member adapted to engage one of the retaining rings to hold the compact container locked.

It is also an object of this invention to provide a compact or cosmetic container with casing sections adapted to carry a mirror and a cosmetic compact, with said casing sections connected by means of hinged metal bands and retaining rings adapted to be quickly engaged on the casing sections to form the completed container.

It is an important object of this invention to provide a cosmetic case or holder the body sections of which are constructed of celluloid or the like, with said sections connected by hinged diametric straps held in place by wire rings engaged over the straps and seated in peripheral grooves formed in the casing sections.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of a cosmetic

case embodying the principles of this invention.

Figure 2 is an enlarged transverse section of the case taken on line II—II of Figure 1. 55

Figure 3 is an enlarged fragmentary rear end view of the cosmetic case taken on line III—III of Figure 1.

Figure 4 is an enlarged fragmentary front view of the device taken on line IV—IV of Figure 1. 60

Figure 5 is a diametric section of a modified form of cosmetic container.

As shown on the drawings:
The reference numeral 1 indicates a dished or concave bottom or body section constructed of a non-metallic product, such as celluloid or galalith, which is casein treated with formaldehyde and subjected to heavy pressure. Removably mounted or frictionally sprung into the bottom section 1 is a retaining ring 2 constructed of celluloid or other suitable material and provided for the purpose of holding a cosmetic compact 3 in place. Associated with the bottom casing section 1 is an upper casing section 4 also constructed of a non-metallic product such as celluloid. The rim or margin of each of the casing sections 1 and 4 is slightly curved inwardly to provide a peripheral groove. 70
Mounted in the cover or top casing section 4 is a mirror 5 frictionally held in place by means of a retaining ring 6 constructed of celluloid or other suitable material. If desired, a pad 7 may be provided in the top 75 section 4 behind the mirror 5. Engaged diametrically over the top casing section 4 is a metal strap or band 8 the ends of which are bent to conform to the shape of the grooved margin of the top casing section. Integrally formed on one end of the metal strap 8 are a pair of spaced hinge sleeves 9 through which a hinge pin 10 is engaged. Integrally formed on the front or opposite end of the top strap 8 is a latch 95 tongue 11. The metal strap 8 is held secured in place diametrically upon the top casing section 4 by means of a wire retaining ring or hoop 12 which engages over the end portions or flanges of the top strap 8 and seats in the peripheral groove of said top section. Engaged diametrically across the bottom

casing section 1 is a bottom strap or band 13 one end of which is provided with a hinge sleeve 14 positioned between the hinge sleeves 9 and having the hinge pin 10 projecting therethrough to form the hinge mechanism. The bottom strap 13 is also held in place by means of a wire ring or hoop 15 which engages over the end portions or flanges of the lower strap 13 and seats in the peripheral 10 groove of the bottom casing section 1. These simple parts form the completed cosmetic case or container having the casing sections 1 and 4 reinforced by the diametric metal straps 13 and 8, respectively, which are 15 hingedly connected at the rear of the device and are held in place on the respective casing sections by the wire rings or hoops. The latch tongue 11 which forms an integral part of the top strap 8 is adapted to snap or 20 spring over the bottom wire ring 15 to hold the compact or casing sections latched in closed position as clearly illustrated in Figure 2.

Figure 5 illustrates a modified form of 25 cosmetic case or container comprising upper and lower casein casing sections 16 each of which is provided with a flat peripheral flange 17. The lower casing section 16 has mounted therein a cosmetic compact 18 held 30 in place by means of a retaining ring or band 19. The upper casing section 16 contains a mirror 20 held in place by a retaining ring 21. Engaged diametrically across the bottom casing section is a metal strap or 35 band 22 one end of which is pivotally connected to an upper strap or band 23 by means of a hinge 24. The upper strap 23 is engaged diametrically across the top casing section 16 and has a latch tongue 25 integrally formed on the front end thereof. Engaged over the end portions of the top strap 23 and encircling the straight flange 17 of the upper casing section is a wire retaining ring or hoop 26 which is held in 40 place by means of retaining tongues or lugs 27 struck from the end portions of the top strap 28 to act as stops or retaining members for holding the ring 26 in place. Engaged over the ends of the lower diametric strap 50 22 and around the flange of the bottom casing section 16 is a retaining wire ring or hoop 28 which is also held in place by means of tongues or lugs 29 struck from the end portions of the lower strap 22. When the 55 cosmetic case is closed the latch tongue 25 is adapted to spring over the lower wire ring 28 to hold the casing sections locked.

The two forms of cosmetic casings or containers are of a simplified construction permitting the device to be easily manufactured at a substantial reduction in cost over earlier compact holders. The devices are adapted to be constructed without use of rivets, screws, or any other similar specific retaining means, thereby permitting the cosmetic 60

casings to be readily manufactured and assembled.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A cosmetic case comprising a pair of body sections constructed of a non-metallic product, metal straps engaged diametrically across said body sections, wire rings engaged over said straps and around said body sections to hold the straps in place, a hinge connecting said metal straps, and latch means formed on said metal straps to hold the casing sections locked to one another. 75

2. A cosmetic case comprising a bottom section and a top section constructed of celluloid, hinged metal straps engaged over said sections, and latch means on said straps for holding the casing sections locked to one another when the top section is in closed position with respect to said bottom section. 90

3. A cosmetic container comprising a bottom section and a top section constructed of a non-metallic product, hinged metal straps engaged diametrically across said sections, wire rings engaged over said straps and around said sections to hold the straps in position thereon, and a latch member formed on one of said straps adapted to engage the wire ring of the opposite casing section to hold the container locker. 95

4. A cosmetic container comprising a pair of casing sections, metal straps engaged diametrically across the outer faces of said casing sections, a hinge for connecting said straps at one side of the container, latch means on said straps for connecting the same at the opposite side of the container, wire rings for holding said straps in place on said container sections, a cosmetic compact and a mirror engaged in said container, and ring members for holding said cosmetic compact and mirror in place. 105

5. A cosmetic case comprising top and bottom sections constructed of a non-metallic material, retaining straps engaged diametrically across the exterior of said sections, means for holding said straps in position on said sections, a hinge for connecting said retaining straps to permit the sections to be swung away from one another into open position, and a latch formed on one of said straps adapted to be latched over the retaining means for the other strap to hold the casing sections latched in closed position. 115

6. A cosmetic container comprising a non-metallic bottom section, a cosmetic compact therein, a ring for frictionally holding the same in place, a non-metallic top section, a 120

125

130

mirror therein, a retaining ring for holding the same in place, hinged straps engaged diametrically across said sections, and means on said hinged straps for latching said sections one to the other.

7. A cosmetic case comprising flanged non-metallic casing sections, metal straps engaged diametrically there-across, and rings

engaged around the flanged portions of said casing sections to hold said straps in position thereon. **10**

In testimony whereof I have hereunto subscribed my name at Chicago, Cook County, Illinois.

JAMES LESLIE YOUNGHUSBAND.
